UNITED STATES PATENT OFFICE.

OTIS M. WALRATH, OF HANOVER, OHIO.

AUTOMATIC CROSSING-GATE.

1,172,327.

Specification of Letters Patent. Patented Feb. 22, 1916.

Application filed March 18, 1915. Serial No. 15,223.

To all whom it may concern:

Be it known that I, OTIS M. WALRATH, a citizen of the United States, residing at Hanover, in the county of Licking and State 5 of Ohio, have invented certain new and useful Improvements in Automatic Crossing-Gates; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15 This invention relates to new and useful improvements in automatic gates for grade crossings, etc., and consists in a simple and efficient apparatus of this nature having various details of construction, combinations and arrangements of parts which 20 will be hereinafter fully described, shown in the accompanying drawings and then specifically defined in the appended claim.

My invention is illustrated in the accompanying drawings, in which:

Figure 1 is a side elevation of one type of the apparatus. Fig. 2 is a sectional view on line 2—2 of Fig. 1. Fig. 3 is a detail view of a clutch mechanism for preventing the reverse motion of the driving shaft. Fig. 4 is a view of a modified form of the apparatus, and Fig. 5 is a sectional view on line 7—7 of Fig. 4.

Reference now being had to the details of the drawings by numeral, 1, 1 designate concrete foundations to which are securely anchored in any suitable manner the pillars 2 which are spaced apart, a recess 3 being formed in the upper portion of the base and in which piers 4 are placed upon the supporting bars for a shaft 5 upon which a grooved idler pulley 6 is mounted. A horizontally disposed cross beam 7 connects the upper ends of the pier and carries suitable hangers in which the shaft 8 is journaled, which shaft has a gear 9 fixed thereto which is in mesh with a gear 10 loosely mounted upon the motor shaft 11 of the motor 12, said motor being mounted in a suitable housing 13, and which gear wheel 10 has a collar or flange 10' notched as at 10''. A collar 11' is fixed to the shaft 11 and has a lug 11'' projecting therefrom which is adapted to engage said notch and cause the gear wheel 10 to be driven forward when the shaft rotates in one direction, but on a reverse movement

said driving shaft 11 will move independent of the gear wheel 10, the latter being at rest in such reverse movement. Pulleys 14 are fixed to said shaft, one between each pair 60 of pillars and about which grooved pulleys 14 the cables 15 pass.

17 designates a horizontally disposed gate to the upper edges of which corresponding ends of the cables 15 are connected, while the 65 other ends of the latter, after being passed about the grooved pulleys 14, are connected to the lower edge of the gate adjacent to each end and in the space intermediate the pairs of pillars, as shown clearly in Fig. 1. 70

Suitable rollers, designated by numeral 18, are attached to the gate, preferably four upon each end or sides of the latter and both top and bottom, and are adapted to work in grooves 19 in the adjacent edges of the pillars and provided for the purpose of reducing the friction incident to contact of parts of the gate to a minimum and prevent any binding of the gate in operation, the upper 75 ends of said grooves serving also to limit the 80 upper movement of the gate by the wheels coming in contact therewith.

Buffer springs 20 are positioned at various locations as shown in the drawings, one upon each concrete foundation or 85 base, and others fastened to the pillars, as shown in Fig. 1 of the drawings and are provided for the purpose of preventing any jar incident to the gate as it is raised or lowered to its limit in either 90 direction. Auxiliary cables, designated by numeral 21, are fastened to the gate and pass about idlers 22 mounted upon the shaft 8, and weights 23 are fastened to the auxiliary cables and are adapted to counterbalance the weight of the gate. 95

In the modified form of the apparatus, as disclosed by Figs. 4 and 5, the device is adapted for use in a pit, parts being modified to adapt the same for such use and in which drawing the top disclosed in Fig. 1 is dispensed with and the working shaft, designated by numeral 42', is located in a pit 41' under the entire structure and which shaft is driven by a motor 42'' in the usual manner and before described, and 43 designates the gate to which the ends of cables 44 are fastened which pass over pulleys 45 mounted upon the pillars 46 and which pass about pulleys 47 upon the working shaft 42''. In this form of the invention, the gate moves through a slot 50 formed in

the ground and which has a hinged closure 51 so arranged that it will open to allow the gate to be raised and remain open until the gate lowers, after which the closure 5 will be automatically thrown down to position to close the slot or opening in the ground to prevent foreign matter falling through the same. Said shaft 42' has drums 22^a fixed thereto about which a cable 21^a 10 winds, said cable passing about a pulley 22^b upon the shaft 22^b, and a weight 23 is fastened to the end of the cable 21^a.

The electrical means for setting the motor in operation may be of any conventional 15 type commonly employed in connection with signals whereby the locomotive passing over tracks will close circuits to operate the motor and set the gate in operation and, as this forms no part of the present invention, 20 detailed description of the same is omitted. Suffice it to say, it is my purpose to so equip railway tracks with electrical connections so that, when trains approach from either 25 direction and pass a switch, the motor will be correspondingly set in operation to close the gates and open the same after the train has passed, and a suitable alarm, either visible or sounding, may be employed in con-

nection with the apparatus to give signal of the approach of trains and closing of the 30 same.

What I claim to be new is:—

An automatic gate for grade crossings, comprising upright pillars spaced apart and arranged in pairs, the inner surfaces of the 35 pillars having channels extending partially the length thereof, a driving shaft journaled upon said pillars, pulleys fixed to the shaft, bases for said pillars with recesses in their upper faces, the end walls of said pillars 40 being flush with the opposite walls of said recesses, a gate, wheels mounted upon the opposite faces of the latter and adapted to travel in said channels and be guided by the walls thereof, the upper movement of the 45 gate being limited by wheels thereof coming in contact with the upper ends of the channels, cables fastened at corresponding ends to the upper and lower edges of the gate and passing about said pulleys.

In testimony whereof I hereunto affix my signature in presence of two witnesses.

OTIS M. WALRATH.
